UNITED STATES PATENT OFFICE.

WILLIAM T. CASTLEBERRY, OF ARTESIA, NEW MEXICO.

FOLDING GATE.

1,377,396.

Specification of Letters Patent.

Patented May 10, 1921.

Application filed July 28, 1920. Serial No. 399,470.

To all whom it may concern:

- Be it known that I, WILLIAM T. CASTLEBERRY, a citizen of the United States, residing at Artesia, in the county of Eddy and State of New Mexico, have invented certain new and useful Improvements in Folding Gates, of which the following is a specification, reference being had to the accompanying drawings.
- 10 This invention relates to an improved vehicle actuated folding gate, and an object of the invention is to provide a gate of this character comprising hinged gate sections mounted in the road bed, and connections between the gate sections, whereby when either one of the gate sections is actuated downwardly by a vehicle in the act of passing thereover, both sections will be closed downwardly, allowing the vehicle to pass.
- 15 Another object of the invention is to provide tensioning means between certain of the operating parts of one gate section and a stationary upright, for returning the gate sections to their raised normal positions 25 after the vehicle has passed over the gate.

A further object of the invention is the provision of means for limiting the gate sections to their normal raised positions.

While the design and construction at present illustrated and set forth is deemed preferable, it is obvious that as a result of a reduction of the invention to a more practical form for commercial purposes, the invention may be susceptible to changes, and the right to these changes is claimed, provided they are comprehended within the scope of what is claimed.

The invention comprises further features and combination of parts, as will be herein-after set forth, shown in the drawings and claimed.

In the drawings:

Figure 1 is a view showing the gate sections of the folding gate in their normal raised position,

Fig. 2 is a sectional view showing the gate sections folded or in their lowered positions, to permit a vehicle to pass thereover, and

Fig. 3 is a plan view of the gate showing the folding gate sections as having been depressed as in Fig. 2.

Referring more especially to the drawings, 1 designates the platform, which may be constructed of any suitable material, preferably wood, and is adapted to be arranged in

the road bed in a proper position in a gate opening of a fence.

Hingedly mounted upon this platform is a pair of folding gate sections 2 and 3, the hinge connections being indicated at 4. Rising upwardly from the platform from opposite sides thereof, and being diagonally arranged, are standards 5 and 6. Pivotedly mounted as at 7 on the standards 5 and 6 respectively are bell crank levers 8 and 9. The arm 10 of the lever 8 is operatively connected as at 11 to the gate section 3. The arm 12 of the bell crank lever 8 has connected to it a rod 13, which in turn is pivotally connected at 14 to the gate section 2. The arm 15 of the bell crank lever 9 is operatively connected to the gate section 2 as at 16. A rod 18 is pivotally connected as at 19 to the other arm 17 of the lever 9. The rod 18 is in turn pivotally connected at 20 to the gate section 3. An upright 21 is mounted on the platform opposite the upright 6, there being a coil spring 22 connected to the upper end of the upright 21, and is in turn connected to the arm 12 of the bell crank lever 8. The arms 12 and 17 of the bell crank levers 8 and 9 are designed to contact with the abutments 23, to limit the bell crank levers 8 and 9 when operative, thereby limiting the folding gate sections 2 and 3 in their depressed or open positions. The ground adjacent the opposite longitudinal side edges of the platform is cut away or channeled as at 24, so as to receive the side flanges of the gate sections, when they have been lowered by the weight of the vehicle, when passing over the gate sections. As soon as the wheels of a vehicle, preferably an automobile, though not necessarily, contact with one or the other of the gate sections, the gate sections will be tilted or moved downwardly, and through the medium of the bell crank connections with the other gate section, it will be automatically moved downwardly. Obviously both gate sections will assume a horizontal position, so that the side flanges 25 of the gate sections will enter the cavities or dug-outs 24 on opposite sides of the platform. As soon as the vehicle passes over both gate sections, they will automatically close, and will assume their normal positions, as shown clearly in Fig. 1.

As previously stated it will be noted that the gate sections 2 and 3 swing upon the pivots 4 while the bell crank levers 8 and 9

oscillate upon their pivots 7. These pivotal centers 4 and 7 are of different radii, therefore the headed pins 11 and 16 travel on arcs relatively different than the travel of the 5 inner ends of the slots in the arms 10 and 15 of the levers 8 and 9, therefore when the gate sections 2 and 3 return to their normal raised positions, the headed pins 11 and 16 will abut the inner ends of the slots of the 10 arms 10 and 15 of the bell crank levers 8 and 9, and limit the gate sections in their raised normal positions.

The invention having been set forth, what is claimed as new and useful is:—

15 1. In a vehicle collapsible gate, the combination with a platform adapted to be embedded in the road bed in a position through a gate opening, of collapsible gate sections hingedly mounted upon the platform with their adjacent ends in normal raised positions, bell crank levers, one of the arms of each of which being pivotally connected to one of the gate sections, supports for the bell crank levers, the other 20 arms of the bell crank levers having rod connections with the opposite ends of the respective gate sections, whereby when either one of the gate sections is depressed by the weight of a vehicle thereon, the 25 other gate section is automatically depressed, to allow the vehicle to pass over the gate sections.

2. In a vehicle collapsible gate, the combination with a platform adapted to be embedded in the road bed in a position through a gate opening, of collapsible gate sections hingedly mounted upon the platform with their adjacent ends in normal raised positions, bell crank levers, one of the arms of each of which being pivotally connected to one of the gate sections, supports for the bell crank levers, the other arms of the bell crank levers having rod connections with the opposite ends of the 35 respective gate sections, whereby when either one of the gate sections is depressed by the weight of a vehicle thereon, the other gate section is automatically depressed, to allow the vehicle to pass over the gate sections, spring means connecting one of the supports and one of the bell crank levers for returning the gate sections to their normal raised positions.

3. In a vehicle collapsible gate, the combination with a platform adapted to be embedded in the road bed in a position through a gate opening, of collapsible gate sections hingedly mounted upon the platform with their adjacent ends in normal raised positions, bell crank levers, one of the arms of each of which being pivotally connected to one of the gate sections, supports for the bell crank levers, the other arms of the bell crank levers having rod 40 connections with the opposite ends of the 45

respective gate sections, whereby when either one of the gate sections is depressed by the weight of a vehicle thereon, the other gate section is automatically depressed, to allow the vehicle to pass over the 70 gate sections, spring means connecting one of the supports and one of the bell crank levers for returning the gate sections to their normal raised positions, and means to be engaged by certain of the arms of said 75 bell crank levers, for limiting the gate sections in their depressed or open positions.

4. In a vehicle actuated road bed gate, the combination with a platform adapted to be sunk in a road bed in a position through a gate opening, the ground upon the opposite longitudinal edges of the platform being cut away to form channels, of collapsible gate sections hingedly mounted upon the platform and having side flanges, which extend down on opposite sides of the platform and adapted to enter said channels formed in the ground, supports mounted upon the platform, bell crank levers pivotally mounted upon said supports, and having certain 90 of their arms connected to the adjacent ends of said gate sections, rods connecting the other arms of the bell crank levers and the ends of the respective opposite gate sections, whereby as one gate section is depressed by the weight of the vehicle thereon, the other gate section is automatically depressed.

5. In a vehicle actuated road bed gate, the combination with a platform adapted to be sunk in a road bed in a position through a gate opening, the ground upon the opposite longitudinal edges of the platform being cut away to form channels, of collapsible gate sections hingedly mounted upon the platform and having side flanges, which extend down on opposite sides of the platform and adapted to enter said channels formed in the ground, supports mounted upon the platform, bell crank levers pivotally mounted upon said supports, and having certain of their arms connected to the adjacent ends of said gate sections, rods connecting the other arms of the bell crank levers and the ends of the respective opposite 105 gate sections, whereby as one gate section is depressed by the weight of the vehicle thereon, the other gate section is automatically depressed, an additional support on the platform, spring means connecting the additional support and one of the arms of one of the bell crank levers for returning the gate sections to their normal positions, and abutment means to be engaged by certain of the arms of the bell crank levers for limiting the gate sections in their depressed or 110 open positions.

6. In a vehicle actuated collapsible gate for road beds, a platform arranged in the road bed through the gate opening, collapsi- 125

- ble gate sections mounted upon the platform, bell crank levers pivotally mounted at diagonally opposite points on the platform, certain of their arms having slot and pin connections with the gate sections, means connecting certain other of the arms of the bell crank levers and the opposite gate sections, whereby the depression of one gate section causes the depression of the opposite gate section, said bell crank levers and the gate sections being pivoted on different radii, whereby the pins of the slot and pin connections will move on a different arc to the inner ends of the slots of the bell crank levers, and contact with the inner ends of the slots, and thereby limit the gate sections in their normal raised positions. 7. In a vehicle actuated collapsible gate for road beds, a platform arranged in the road bed through the gate opening, collapsible gate sections mounted upon the platform, bell crank levers pivotally mounted at diagonally opposite points on the platform, certain of their arms having slot and pin connections with the gate sections, means connecting certain other of the arms of the bell crank levers and the opposite gate sections, whereby the depression of one gate section causes the depression of the opposite gate section, the arc of movement of the pins of the slot and pin connections being relatively different than the arc of movement of the inner ends of the slots, thereby causing the pins to abut the inner ends of the slots and limit the gate sections in their normal raised positions, spring means for returning the gate sections to their normal raised positions, and means engaged with certain of the arms of the bell crank levers for limiting the gate sections in their depressed or open positions. 8. In a vehicle actuated collapsible gate for road beds, the combination with a platform arranged in the road bed through the gate opening, of collapsible gate sections hingedly mounted upon the platform and having adjacent ends in normal raised positions, means connecting the gate sections, whereby the depression of either gate section causes an automatic depression of the other gate section, said means including an arm having slots, means connected to the said sections and engaging said slots, said slots moving on a different radii to the sections, whereby the last means may contact with certain ends of the slots and limit the sections in their normal raised positions.
- In testimony whereof I hereunto affix my signature.
- WILLIAM T. CASTLEBERRY.
